United States Patent Office

Des. 204,179
Patented Mar. 22, 1966

204,179

REFRIGERATED SHOWCASE

Karl A. Weber, Los Angeles, Calif., assignor to Walter
Kidde & Company, Inc., a corporation of New York

Filed Nov. 12, 1964, Ser. No. 82,565

Term of patent 14 years

(Cl. D80—11)

FIG. 1.

FIG. 2.

FIG. 3.

FIG. 4.

FIGURE 4 is a cross-sectional end view taken along line 4-4 of FIGURE 3. The rear of the refrigerated showcase is essentially plain and unornamented except as illustrated in FIGURE 4.

I claim:

The ornamental design for a refrigerated showcase, substantially as shown.
